UNITED STATES PATENT OFFICE.

JUNE K. CHINN, OF SEATTLE, WASHINGTON.

DESIGN FOR AN AUTOMOBILE LAMP.

Application filed May 1, 1925. Serial No. 13,271. Term of patent 14 years.

To all whom it may concern:

Be it known that I, JUNE K. CHINN, a citizen of the United States, and a resident of Seattle, in the county of King and the State of Washington, have invented a new, original, and ornamental Design for an Automobile Lamp, of which the following is a specification, reference being had to the accompanying drawings, forming a part thereof.

In the drawings,

Fig. 1 is a front view.

Fig. 2 is a side view of the article showing my new design.

I claim:

The ornamental design for an automobile lamp, as shown.

JUNE K. CHINN.
